(57) **CLAIM**

The ornamental design for an ethernet tester, as shown and
described.

DESCRIPTION

FIG. 1 is a front right isometric view of an ethernet tester
showing my new design.

FIG. 2 is a front elevational view thereof.

FIG. 3 is a rear elevational view thereof.

FIG. 4 is a left elevational view thereof.

FIG. 5 is a right elevational view thereof.

FIG. 6 is a top plan view thereof; and,

FIG. 7 is a bottom plan view thereof.

Portions shown in phantom lines are for purposes of enable-
ment and are not a part of the claimed design.
